UNITED STATES PATENT OFFICE

2,428,064

COARSE YARN CATCHER

Walcott H. Bussiere, Pittsfield, Mass.

Application June 28, 1946, Serial No. 680,273

3 Claims. (Cl. 57—107)

1

This invention relates to improvements in spinning apparatus and is directed more particularly to improvements in apparatus for spinning yarn.

The principal objects of the invention are the provision of apparatus adapted to be associated with a spinning frame to catch and break the roving, as it is being wound onto the bobbin, when the roving is heavier or coarser than is desired or will provide a yarn which is heavier or coarser than it is desired to produce.

In spinning the roving leaves the roller beam and passes through a traveler which rotates around a ring surrounding a rotatable bobbin that reciprocates axially and relative to the ring. The reciprocation of the bobbin while it rotates fills up the bobbin with the desired and particular form or shape of winding.

As the yarn is wound onto the bobbin, which reciprocates up and down within and relative to the ring and traveler, the action is such that the windings on the bobbin are of greater diameter at one point than at another point longitudinally thereof. As an instance the diameter of the winding may be greater adjacent the lower end of the bobbin than adjacent the upper end thereof so that different diameters of the winding are during the spinning operation located in the ring where the yarn passes from the traveler onto the bobbin. The yarn is wound onto different diameters accordingly as the bobbin moves up and down.

The high speed of rotation of the bobbin causes the roving to loop outwardly and upwardly from the traveler whereby it extends outwardly a greater distance from the axis of the bobbin or sweeps through a greater radius when a greater diameter of winding is in the ring than when a smaller diameter is in said ring. Thus while the bobbin moves up and down relative to the ring and traveler the sweep of the loop formed by the roving going to the traveler varies in diameter according to the diameter of the winding on the bobbin. The radial distance from the loop to the winding remains substantially constant while the characteristics of the roving remain constant. That is the distance from the loop of roving to the winding is substantially constant at all diameters of winding.

When, however, the roving becomes heavier or coarser the loop and its sweep becomes greater, or the roving extends outwardly from the winding on the bobbin a greater distance regardless of the diameter of the winding onto which the yarn is being wound. As the bobbin reciprocates up

2

and down and while the roving is heavier or coarser the loop at all diameters of the winding extends outwardly a greater distance than normal.

According to this invention, means is provided for catching and breaking the roving when it becomes heavier or coarser than normal so that the loop sweeps around at a greater radius.

In order to produce yarn having certain desired characteristics the roving must have certain characteristics and when the roving becomes coarser it is desired to break it so that it will not be wound on the bobbin. This is accomplished in a broad way by hook means which normally is out of the path of the roving as it loops out and sweeps around in passing to the traveler but which is adapted, when the roving becomes coarser and assumes a greater loop and sweep, to catch and break the roving whereby the coarser roving will not be wound onto the bobbin.

The hook means is movable towards and away from the bobbin as the bobbin moves up and down in such a manner that the hook is disposed at a certain distance from the winding on the bobbin at all of its diameters. While the roving retains its normal characteristics it is not caught by the hook. When, however, the roving becomes coarser so as to loop outwardly a greater distance than normal it is caught by the hook. By moving the hook means in and out it is positioned so as to catch the roving at all diameters of the bobbin when it is running heavier than normal.

With the foregoing and various other novel features and advantages and other objects of my invention as will become more apparent as the description proceeds, the invention consists in certain novel features of construction and in the combination and arrangement of parts as will be hereinafter more particularly pointed out in the claims hereunto annexed and more fully described and referred to in connection with the accompanying drawings wherein:

Fig. 1 is a front elevational view of yarn catcher apparatus embodying the novel features of the invention;

Fig. 2 is an end elevational view of the apparatus shown in Fig. 1; and

Fig. 3 is an enlarged sectional plan view on the line 3—3 of Fig. 1.

Referring now to the drawings more in detail the invention will be fully described.

So much of a spinning frame as is necessary to facilitate a clear understanding of the invention is shown in dash lines. Longitudinally extending roller beams at opposite sides of a frame

are represented by 2, a part of the frame is shown at 4 and side rails are indicated by 6. Traveler guide rings 8 are carried by the rails 6 around which travelers 10 rotate. Bobbins 12 reciprocate up and down through openings in the rail as they are rotated. Rovings extend downwardly from mechanism on the roller beams, through the travelers 10 onto the rotating bobbins whereby the spinning is accomplished and the yarn is wound on the bobbins.

As shown in Fig. 1, the roving loops outwardly at R and sweeps around the bobbin. The distance from the winding to the loop of the roving is substantially constant while the roving retains the desired normal characteristics. With this constant distance the roving is at a greater distance from the axis of the bobbin when the winding of a greater diameter is being served than when a smaller diameter is in the ring. When the roving becomes coarser the loop becomes relatively greater or the distance between the winding and loop becomes greater at all diameters of the winding.

The apparatus of this invention includes hooks for catching and breaking the roving when they become heavier so as to form a greater loop or sweep of the loop as will now be described.

Supports 20 are provided for the front and rear sides of a spinning frame at opposite ends thereof, and they may be secured at upper and lower ends to parts of the frame. There may be as many such supports at front and rear sides of the frame as may be desired and will depend on the length thereof. The supports may be secured together by any suitable means to provide a strong rigid supporting structure.

Guide brackets 22 are secured to the supports 20 in any convenient manner and have upper and lower spaced arms 24 and an outer end member 26 secured thereto. A longitudinally extending hook bar 26 has opposite end portions disposed in these brackets 22. Rods 28 carried by the bar are slidable in the members 26 and spring 30 around said rods 28 between the bars and members 26 urge the bar inwardly. The rods 28 may be secured to the member 26 with the bar slideable thereon, if desired.

In Fig. 2 the bars 26 are shown in retracted positions and are moved outwardly by the cams which are formed to permit retraction thereof by the springs 30 which urge the bars against the cams.

When the shafts 36 in Fig. 2 are rotated clockwise the bars 26 are moved outwardly. When the said shafts are rotated in a reverse direction the bars move inwardly to the supports 20.

The shafts 36 are preferably rocked simultaneously and is accomplished in one way by arms 40 which are fixed thereto and have free ends pivotally connected at 42 to a link 42'.

An arm 46 is fixed to one of the shafts 36 and a link 48 connected thereto at 50 has a roll 52 on its lower end which is in a groove 54 of a cam 56. Said cam may be fixed to such a shaft as 58 which is rotatable in frame part 4 of the spinning frame. The lower end of link 48 is provided with a slot 49 whereby it is guided on shaft 58 for up and down movements.

As the bobbins rotate and move up and down relative to the rails, the different diameters of winding are served. The bars move in and out accordingly as the bobbins move up and down so that the hooks are at a certain distance from the winding and bobbin. This distance is normally such that the loops of roving in their cir-

cular sweep will pass in front of and forwardly of the hooks.

When however a roving becomes coarser the loop becomes greater so that it sweeps around the bobbins at a greater distance from the axis of the spindle and is caught by a hook and is broken.

The invention may be embodied in other specific forms without departing from the essential characteristics thereof. Hence, the present embodiments are therefore to be considered in all respects merely as being illustrative and not as being restrictive, the scope of the invention being indicated by the appended claims rather than by the foregoing description, and all modifications and variations as fall within the meaning and purview and range of equivalency of the appended claims are therefore intended to be embraced therein.

What it is desired to claim and secure by Letters Patent of the United States is:

1. Apparatus for engaging rovings on a spinning frame as they are being wound on a row of bobbins rotating on vertically disposed and longitudinally spaced axes comprising in combination, longitudinally spaced vertically disposed supports adapted to be located at opposite ends of a row of bobbins, guide means fixed on said supports, a hook bar having opposite ends slidably supported in said guide means for movements of the bar in opposite directions in a horizontal plane, longitudinally spaced hooks fixed to said bar for engaging rovings, operating means acting on opposite ends of the hook bar for moving it in one direction, and yielding means acting on opposite ends of the hook bar for moving it in an opposite direction.

2. Apparatus for engaging rovings being wound on a longitudinally spaced row of bobbins rotatable on vertical axes of a spinning frame comprising in combination, longitudinally spaced vertically extending supports adapted to be located at opposite ends of a row of bobbins, a longitudinally extending horizontally disposed hook bar and coacting guiding means between opposite ends of the bar and said supports adapted to facilitate movements of the bar in opposite directions relative to the supports and in a horizontal plane, hooks adapted to be engaged by rovings fixed to said bar in spaced relation, bearing means fixed to said supports, a longitudinally extending oscillatable cam shaft in substantial parallelism with said hook bar having opposite ends journalled in said bearing means, cams fixed on said shaft adjacent opposite ends of the bar engageable therewith adapted as the cam shaft oscillates in one direction, spring means at opposite ends of the bar urging it against said cams and in an opposite direction, and means to oscillate said cam shaft in opposite directions.

3. Apparatus for engaging rovings being wound on spinning frame bobbins which are rotatable on vertical axes and arranged in transversely spaced rows with the bobbins of a row longitudinally spaced comprising in combination, longitudinal spaced vertically extending supports arranged in two pairs with the supports of a pair adapted to be located at opposite ends of a row of bobbins, longitudinally extending horizontally disposed hook bars and guiding means between opposite ends of the bars and the supports of a pair thereof adapted to facilitate movements of the bar in opposite directions relative to the supports and in horizontal planes, hooks adapted to be engaged by rovings fixed to said bars in

spaced relation, bearing means fixed to the supports of the pairs thereof, longitudinally extending oscillatable cam shafts in substantial parallelism with said hook bars having opposite ends journalled in said bearing means, cams fixed on said cam shafts adjacent opposite ends of the hook bars engageable therewith and adapted as the cam shafts oscillate in one direction to move the said hook bars in one direction, spring means at opposite ends of the hook bars urging them against said cams and in opposite directions, means connected to one of said cam shafts for oscillating it in opposite directions, and op-

erative means connecting said cam shafts whereby as said one cam shaft is oscillated the other cam shaft is oscillated simultaneously therewith in opposite directions.
